BLADE FASTENING DEVICE FOR SAWS

David T. Anderson, Montreal, Quebec, Canada,
assignor to Harold C. A. Walby, Montreal,
Quebec, Canada

Application April 2, 1936, Serial No. 72,310

4 Claims. (Cl. 145—33)

The present invention relates to blade fastening means for frame saws and the like.

An object of the invention is the provision of a saw having a blade fastening device which is 5 adjustable on the frame.

Another object of the invention is the provision of a saw having a blade fastening device designed so as to enable variation in the tension of the blade and to counter-act decrease in the 10 tensional effect of the frame.

A further object of the invention is the provision of a blade fastening device of the aforesaid character which may be employed on conventional saw frames and may be adjusted without the use of tools.

A still further object of the invention is the provision of a blade fastening means for saws which is relatively simple and durable in construction.

Other objects and advantages of the invention 20 will become apparent as the description progresses.

In the accompanying drawing forming a part of this specification and in which like reference characters are employed to designate corresponding parts throughout the same:

Figure 1 is a side elevational view of a saw equipped with the improved blade fastening device,

Figure 2 is a fragmentary perspective view of the same,

Figure 3 is a fragmentary side elevational view of the saw frame showing the blade fastening device in section,

Figure 4 is a similar view showing the manner of releasing the device, and

Figure 5 is an enlarged sectional view taken on the line 5—5 of Figure 3.

Referring to the drawing, wherein for the purpose of illustration is shown a preferred embodiment of the invention, A generally designates a saw frame of the type commonly known as a "bow" frame used in conjunction with web or buck saws. The frame A may be formed of 40 metal tubing, wood or the like, and is bent to provide a straight longitudinal body portion 10 and end arms 11 and 12 arranged obliquely to the longitudinal section 10 and projecting at outwardly or diverging angular inclinations. The 45 arm 12 is somewhat longer than the complementary arm 11, inasmuch as the end extension 13 is adapted to provide a handle for the operation of the saw.

The primary feature of the invention is the 55 provision of a blade fastening device, generally

indicated at B, mounted so as to be slidably adjustable on the frame arm 12 and engageable with one end of the saw blade. The device B which may be formed of sheet metal or in any suitable manner embodies a body portion 15, 5 shaped to slidably embrace the frame arm 12 and loosely conforms to the cross sectional contour of the arm. At the inner side, the body is formed with a pair of parallel apertured complementary arms 16 arranged in parallel closely spaced position and disposed to receive therebetween one end of a saw blade 17. A bolt 18 is adapted to be fitted through the apertures in the arms 16 and through a registering aperture in the blade for releasably connecting the blade to the 15 arms. At the opposed outer side portion of the approximately loop-shaped body 15 is formed a tapered laterally projecting lip 20 having a flat top surface for a purpose which will be later described.

At the top outer edge, the body 15 of the fastening device is formed with a longitudinally extending relatively narrow and tapered tongue 21 having a struck out or dented inwardly protruding boss 22 intermediate its ends. This boss 25 is designed to engage any one of a number of indentations or cavities 23 formed at predetermined longitudinally spaced intervals on the frame arm on which the device is fitted.

The slidable device is releasably held in set 30 position on the arm by means of a fastening ring 25 loosely fitted on the frame arm and having an interior taper so that it may be slidably disposed over the tongue in order to press the tongue against the arm and more particularly 35 to retain the boss 22 of the tongue into a selected indentation 23 in the arm.

Thus, the device is initially disposed in such 40 position on the arm as to fasten the saw blade at suitable tension on the frame for predetermined work. If, for use in different work, it is 45 advisable to vary the tension of the blade, the fastening ring 25 is struck by the foot of the worker so that it is slid longitudinally on the arm in a direction away from the device and to disengage the end portion of the tongue 21. The device is then dislodged from its adjusted position by disposing the frame in an upright position and placing the foot on the lip 20. If the tension of the blade is to be increased, the weight 50 of the body is placed on the foot held on the lip, so as to slide the fastening device B downwardly on the frame arm and toward the lower handle portion, as shown to advantage at Figure 4, and until the boss 22 enters the desired cavity 23 in 55

the frame. The securing ring 25 is then slid downwardly to firmly compress the tongue against the arm and to secure the device in the set position.

5. Such adjustment of the device not only enables variation in the tensional mounting of the saw blade but is useful in counter-acting a loss or decrease in the tensional effect of the bow frame, enabling prolonged use of the frame which would 10 be discarded with the fastening devices heretofore commonly used.

Furthermore, the construction of the device is such as to enable the same to be adjusted manually and without tools of any kind and also enables adjustment in clearance of the saw, that 15 is, in the space between the blade and the longitudinal portion 10 of the frame. The formation of the adjustable device is such as to retain the blade in proper alignment in the various adjusted 20 positions.

As is readily apparent from Figure 1, one end of the blade 17 is attached to the end of the short frame arm 11 by connection with a stationary pin 27 removably positioned in apertures 25 in opposed sides of a bifurcated structure at the end of the arm. Consequently, the adjustment of the movable fastening device B on the longer frame arm 12 effects a pivotal movement of the blade with respect to the fastening pin 27 and 30 avoids binding or distortion of the blade.

It is to be understood that the form of my invention herein shown and described is to be taken as a preferred example of the same, and that various changes as to the shape, size and arrangement 35 of parts may be resorted to without departing from the spirit of the invention or the scope of the subjoined claims.

Having thus described my invention, I claim:—

1. In a saw including a frame having a slanting 40 end portion provided with longitudinally spaced cavities, a blade fastening device embracing the said arm and slidably longitudinally thereon, a projection on the device for detachably engaging one end of the saw blade, a boss projecting inwardly 45 on the sliding device engageable with the respective cavities on the frame, a ring slidable to press a portion of the sliding device against the arm of the frame so that the boss will engage

one of the cavities in the frame for releasably securing the device in adjusted position, and an outwardly projecting lip on said sliding device for adjusting the device on the frame.

2. A device of the character described comprising a saw frame having a slanting end portion provided with longitudinally spaced cavities, a blade fastening member slidably fitted on the said end portion of the frame, means on said fastening member for engaging one end of a saw blade, a tongue formed integral with the fastening member and normally extending substantially parallel with and alongside the end of the saw frame in both operative and inoperative positions of said tongue, a boss on the tongue engageable with the cavities in the frame, and means for releasably securing the said boss in a selected cavity.

3. In a saw including a frame having a slanting end portion provided with longitudinally spaced cavities, a blade fastening device embracing the said end portion and slidably longitudinally thereon, a tongue formed integral with the fastening device and normally extending substantially parallel with and alongside the end of the saw frame in both operative and inoperative 25 positions of said tongue, a boss projecting inwardly from the tongue engageable with the respective cavities on the frame, and means for releasably holding the boss in engagement with a selected cavity for releasably fastening the slide 30 member in adjusted position on the frame.

4. In a saw including a frame having a slanting end portion provided with longitudinally spaced cavities, a blade fastening device embracing the said end portion and slidably longitudinally thereon, a tongue formed integral with the fastening device and normally extending substantially parallel with and alongside the end of the saw frame in both operative and inoperative 40 positions of said tongue, a boss projecting inwardly from the tongue engageable with the respective cavities on the frame, and a ring slidable to press the tongue against the end portion of the frame so that the boss will engage one of the cavities therein for releasably securing the device 45 in adjusted position.

DAVID T. ANDERSON.
